Harlow M. Davis

UNITED STATES PATENT OFFICE

JOHN B. HADAWAY, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

HEEL BASE

Application filed May 31, 1929. Serial No. 367,586.

This invention relates to heel bases, and particularly to bases to which it is intended that rubber heels shall be attached.

The usual base for rubber heels is plano-convex and comprises one or more flat, full-sized lifts of leather with a leather rand secured thereto at the attaching face of the base to provide a concave or cupped surface to fit the convex surface of the heel seat of a shoe. Heretofore it has never been found practical to economize in the manufacture of heel bases by the use of leatherboard or other leather substitute for the full-sized lift, because such materials were not sufficiently tough to withstand the abrasion resulting from the chafing action of the rubber heel upon the marginal portion of the outer face of the heel base, which occurs at every step taken by the wearer of the shoe. This chafing action is an incident to the alternate deformation and recovery of the rubber as the weight of the wearer is applied to and removed from the heel, and is so vigorous that a leatherboard surface subjected to it is soon frayed and disintegrated.

It is an object of the present invention to provide a practical, satisfactory heel base which can be manufactured more cheaply than the all-leather heel bases now commonly used, and I have discovered that this can be accomplished by facing the marginal portion of a full-sized lift of cheap material, such as leatherboard or any of the common leather substitutes, with a strip of tough material capable of resisting disintegration from the chafing action of a rubber heel; the facing strip being upon that face of the lift to which the rubber heel is to be applied, as distinguished from the attaching face of the lift to which a rand has heretofore been applied to produce a cupped surface.

Conveniently, though not necessarily, the facing strip may be made of leather and may, as illustrated herein, resemble a rand in that it may be wedge shaped in cross section, but its position, as above stated, is very different from that of the usual rand and it performs a service of primary importance in withstanding the chafing action of the rubber heel,

which service is not performed at all by the ordinary rand.

As shown in the accompanying drawings my improved heel base may be plano-convex in form, to fit the heel seat of a shoe and provide a plane face for the reception of a rubber heel, the facing strip constituting the marginal portion of the plane face. The remainder of the base may consist of one or more concavo-convex lifts of leather substitute, for example leatherboard.

These and other features and advantages of the invention may be better understood and appreciated from reading the following detailed description of one embodiment of the article and a manner of practising the process in connection with the accompanying drawings, in which

Fig. 1 is a perspective view illustrating the first step in the manufacture of my improved heel base;

Fig. 2 is a transverse section in the plane II-II of Fig. 1;

Fig. 3 is a perspective view of the heel base in its final form; and

Fig. 4 is a transverse section in the plane IV-IV of Fig. 3, showing also the manner in which a rubber heel may be applied to the base.

Referring now to Fig. 1, 10 indicates a full-sized, substantially flat lift of material cheaper than leather such, for example, as leatherboard or any other suitable leather substitute. It is well-known to those skilled in the art that manufactured materials of this class are quite satisfactory for use in heels for many classes of shoes and that very substantial economies are obtained by using them instead of leather, not only because such materials are intrinsically cheaper than leather but also because, being manufactured in sheets of any desired size and thickness, they can be cut to produce a minimum amount of waste. Large quantities of leather substitutes are, therefore, used in the manufacture of heels but because of the well-known fact that such materials, although satisfactory in other parts of a heel, will not withstand the abrasion resulting from the chafing action of a rubber heel upon the marginal

portion of the outer face of a heel base it has heretofore been considered necessary to employ a leather lift in this position.

In manufacturing my improved heel base, 5 a facing strip 12 of tough material, capable of resisting disintegration from the chafing action of a rubber heel, is applied and attached to the marginal portion of one face of the lift 10. While it may be preferred 10 to make the facing strip 12 of leather, it is within the scope of the invention to employ any other suitable tough material which will endure under the chafing action of a rubber heel.

15 As shown, the facing strip 12 is wedge-shaped in cross section, resembling an ordinary rand, and in practice a common leather rand, which is a regular article of commerce, would be used. The rand or facing strip 12 20 may be attached to the lift 10 by tacks or cement in any of the well-known manners of attaching rands but I prefer to attach it with rubber latex cement.

The blank prepared as above-described and 25 appearing as shown in Fig. 1 is next molded in a heel compressing machine to the form shown in Figs. 3 and 4 wherein the originally flat exposed face 14 of the leatherboard lift 10 becomes concave and the face to which 30 the wedge-shaped strip 12 is secured becomes plane, any wrinkles or irregularities in the facing strip being removed by the compressing and molding operation. The concave face 14 of the heel base is formed to fit the heel seat of a shoe and the plane face is 35 adapted to receive a rubber heel, as indicated at 16 in Fig. 4.

From Figs. 3 and 4 it will readily be seen that the marginal portion of the outer face 40 of the heel base, which is the portion detrimentally affected by the chafing action of the rubber heel, consists of leather or other suitable abrasion resisting material, and experience has demonstrated that this heel base is 45 entirely satisfactory for a large proportion of rubber heeled shoes although it can be manufactured at considerably less cost than can the heel bases heretofore used commercially.

Having described the invention what is 50 claimed as new and desired to be secured by Letters Patent is:

1. A heel base for rubber heels comprising a full-sized lift of cheap material subject to disintegration from the chafing action of a rubber heel and a facing, consisting of a 55 strip of tough material capable of resisting such disintegration, upon the marginal portion of that face of the lift to which a rubber heel is to be applied.

2. A heel base for rubber heels comprising a full-sized lift of leather substitute and a strip of leather of wedge-shaped cross section attached to the marginal portion of that face of the lift to which a rubber heel is to 65 be applied.

3. A plano-concave heel base for rubber heels, said heel base comprising a full sized lift of leather substitute and a rand-like strip of leather attached to said lift and constituting the marginal portion of that face of the heel base to which a rubber heel is to be applied.

4. A heel base for rubber heels comprising a body portion of material cheaper than leather, of the size and contour of the desired base, and a strip of leather attached to the rubber heel receiving face of said body portion, the peripheral edges of the body portion and strip being substantially flush with each other.

5. A heel base for rubber heels comprising a concavo-convex body portion of leatherboard to the marginal portion of the convex face of which is attached a strip of leather of wedge-shaped cross section, providing an approximately flat surface of leather for engagement with the marginal portion of the attaching face of a rubber heel.

In testimony whereof, I have signed my name to this specification.

JOHN B. HADAWAY.
